(57) **CLAIM**

The ornamental design for a tea strainer, as shown and described.

DESCRIPTION

FIG. 1 is a front, right side perspective view of a tea strainer embodying my new design;

FIG. 2 is a front elevational view thereof;

FIG. 3 is a rear elevational view thereof;

FIG. 4 is a right side elevational view, left side view being the mirror image thereof;

FIG. 5 is a top plan view thereof;

FIG. 6 is a bottom plan view thereof; and,

FIG. 7 is a front, right side, exploded perspective view of a tea strainer shown in an open position.

In the drawings, the broken lines in FIGS. 6 and 7 depict portions of the design that form no part of the claim.

1 Claim, 4 Drawing Sheets
